AUTOMATIC MOLD PROTECTOR FOR TYPE CASTING MACHINES

James M. Dent, Cleveland, Ohio, assignor to Composing Room Engineers, Inc., Cleveland, Ohio, a corporation of Ohio

Application June 3, 1935, Serial No. 24,688

5 Claims. (Cl. 199—52)

The present invention relates to a device for preventing injury to the molds, liners and the casting ejector devices of a type casting machine, by preventing operation of the casting ejector when the ejecting elements are not properly positioned with respect to the mold.

In type casting machines an ejector is commonly used which consists of a series of narrow superimposed blades, any number of which may be connected to the ejector actuating mechanism to provide an ejector plunger which corresponds in width to the length of the mold slot and pushes out the slug or casting without damaging the casting or the walls of the mold. An adjustable ejector blade selector device is employed by means of which any desired number of ejector blades may be disconnected from the ejector operating mechanism. It sometimes happens, however, that the operator fails to adjust the ejector blade selector lever to the proper position upon insertion of a different mold liner or an improper change in adjustment may escape the notice of the operator, in which event the operation of the ejector may damage both the mold liner and the ejector blades and also the casting.

This invention has for its object to provide a device to prevent the operation of the ejector in the event that the blade selector is improperly positioned, thereby preventing injury to the mold and enabling the operator while the machine is stopped to properly set the ejector blade selector for the particular mold which is being used.

A further object of the invention is to provide automatic mold protector which can be applied to a linotype machine without any alteration whatever to the mechanism of the machine, which does not require any adjustment of the parts of the machine, and which does not impair the operation of any of the parts of the machine.

A further object is to provide a mold protector comprising a small number of inexpensive parts which can be quickly and easily attached to a type casting machine.

With the above and other objects in view the invention may be said to comprise a device as illustrated in the accompanying drawings, hereinafter described and particularly set forth in the appended claims, together with such variations and modifications thereof as will be apparent to one skilled in the art to which the invention appertains.

Reference should be had to the accompanying drawings forming a part of this specification, in which:

Figure 1 is a perspective view showing the de-

vice of the present invention, the mold disk, and other parts of a type casting machine with which the device of the present invention coacts;

Fig. 2 is a fragmentary front elevation of a portion of the mold disk and the selective trip actuating device;

Fig. 3 is a side elevation of the adjustable trip rod supporting device shown in Fig. 2;

Fig. 4 is a fragmentary side elevation of the mold protecting trip device of the present invention;

Fig. 5 is a section taken on the line indicated at 5—5 in Fig. 4;

Fig. 6 is a section taken on the line indicated at 6—6 of Fig. 4;

Fig. 7 is a sectional view showing the connection between the operating bar and the upper end of the trip plate lever.

As shown in the accompanying drawings, the device of the present invention is applied to a type casting machine having a mold disk 1 in the form of a gear wheel which carries one or more molds 2 mounted in slots in the web of the disk. The mold disk usually has four mold receiving slots. Molds may be mounted in as many of the slots as desired. In the drawings four molds are shown. Each mold consists of a body portion 3, a keeper 4 which is provided with a groove 5 to receive the lugs of the matrices which are fed to the mold disk in rows so as to close one side of the mold slot and form the type at one edge of a slug cast in the slot. The mold also has a cap 6 and liners 7 and 8 which are interposed between the ends of the cap and keeper to determine the width and thickness of the mold cavity. The left hand liners 7 differ in thickness but are always of the same width, while the right hand liners 8 correspond in thickness to the liners 7 but vary in width, the width of the liner 8 determining the length of the mold cavity.

In the operation of the machine the matrices are assembled in rows of a length corresponding to the length of the mold cavity and a row of matrices is fed into place on the outer side of the mold during the interval between the ejection of a slug or casting from the mold and the injection of molten metal into the mold.

As well understood in the art, a series of distributing and transfer devices are employed for feeding the matrices up to and transferring them to the mold. Axial and rotative movements are imparted to the mold disk at intervals during the operation of the machine, and these motions are timed with the motions of the matrix transferring devices, the molten metal injector, and

the casting ejector. The cycle of operation is performed by means of a series of cams mounted side by side on a shaft and driven from a suitable source of power through a clutch mechanism which is operated so as to impart a complete revolution to the cam shaft and to disconnect the camshaft after the revolution is completed, the one revolution of the camshaft performing the entire cycle of operation from the feeding of matrices to a mold to the ejection of a casting from the mold.

As herein shown, power is derived from a suitable pulley 9 which may be driven by a belt from a suitable line shaft. The pulley 9 is mounted on a shaft 10 from which the camshaft is driven, one cam 11 being shown herein, the pulley 9 being connected to the shaft 10 by a clutch 12. The cam 11 is the line delivery cam which carries a stopping pawl which operates the clutch 12 to release the pulley 9 from the shaft 10 upon the completion of the revolution of the camshaft and a safety pawl which operates the clutch upon failure of certain of the matrix transfer devices.

25 The clutch 12 is actuated by a shifter lever 13 which may be operated manually by means not shown and which may also be operated automatically through levers actuated by a pawl on the cam 11. The lower automatic stop lever 14 which engages with the shifter lever 13 has a projecting portion 15 intermediate its ends which is connected by a pivot 16 to a vertical post 17. The upper automatic stop lever 18 is attached at its inner end by a pivot 19 to the post 17 and has a substantially horizontal upper edge portion 20 which may be engaged by a stop pawl on the cam. The lever 18 also has a downwardly projecting arm 21 which carries a set screw 22 which is engageable with the upper end of the lower lever 14. By adjustment of the screw 22 the extent of movement of the lever necessary to disengage the clutch may be regulated. On the cam 11 there is mounted a stopping pawl 23 which is so controlled as to engage with the lever 18 only in the event there is a failure of the matrix transfer devices which would interfere with the proper delivery of matrices to the mold. Pawl 23 is pivoted to swing laterally from a position in alignment with the lever 18 to a position laterally of the lever 18 in which the pawl will pass the lever 18 without engaging it. When the matrix transfer mechanism is functioning normally, pawl 23 is held laterally of the lever 18 so that it will pass the lever 18 without engaging it as shown in Fig. 5 of the drawings, it being held in this position by means not shown which is controlled by the matrix feeding mechanism.

50 So far as the present invention is concerned, it may be assumed that the pawl 23 has a path of movement to one side of the lever 18.

55 Referring to Fig. 1 of the drawings, molten metal is injected into the mold when the mold is in its uppermost horizontal position, and after the metal is injected into the mold a rotary movement is imparted to the mold which brings the mold into a vertical position at the right hand side of the mold in alignment with the ejector blade 24. A sufficient number of blades 24 are 60 provided to form an ejector plunger of a width corresponding to the maximum width of the casting slot. A selective mechanism is provided for disengaging as many of the blades 24 as desired from the ejector actuating mechanism so that 65 all of the blades which are aligned with the liner

8 are rendered inoperative and only the blades which are in alignment with the mold aperture are advanced upon actuation of the ejector.

65 The operation of the blades is controlled by a selector operating lever 25 which is adjusted by the operator in a proper position for the particular length of slug or casting being formed in the mold. An indicator bar 26 is attached to the selector operating lever 25 and the upper end of the bar 26 is provided with numbered graduations 10 which are visible through an aperture 27 in the frame 28 of the machine. The numbers on the indicator bar 26 correspond to the numbers of the liners 8 which are employed, so that the operator can readily adjust the selector operating 15 lever to the proper position for the particular liner employed in the mold.

20 The mechanism so far described is well known in the art, being the mechanism employed in type casting machines of the type most commonly used, 20 the parts of the type casting machine described being those with which the device of the present invention cooperates.

25 The device of the present invention is a selectively operated trip device which is controlled by the adjustment of the ejector blade selector and which is actuated when there is an improper adjustment of the selector to cause actuation of the clutch lever by the stopping pawl 23. On the frame 28 there is mounted a lever 30 which is 30 pivoted intermediate its end to a bracket 31 fixed to the frame. The pivotal axis of the lever 30 is substantially parallel with the axis of the mold disk 1 and the lever is positioned outwardly of the periphery of the disk. The outer end of the 35 lever is connected by a link 32 with the indicator bar 26, link 32 being connected by a pivot 33 to the outer end of the lever and extending downwardly and inwardly to a pivot 34 connecting it to the bar 26. At its inner end the 40 lever 30 has an arm 35 extending downwardly toward the periphery of the disk 1 and this arm is provided with an elongated slot 36. The lower end of the slot 36 provides a support for an operating rod 37 which is disposed 45 substantially parallel with the axis of the disk and extends across the periphery of the disk. At its outer end the rod 37 has a downturned end providing a finger 38 which overlies the margin of the disk 1. At one end of the mold on the mold 50 disk which is being used there is mounted a selector plate 39 which is so positioned with respect to the mold that it will be brought to a position behind the downturned finger 38 of the operating rod 37 when the mold is brought to ejecting position. Each selector plate 39 is provided with a slot 40 to receive an attaching screw 41 for securing the plate to the face of the disk, and at its outer edge is provided with a flange 42 which has a notch 43 of a width to receive the finger 38 55 of the trip operating rod.

60 As many different selector plates 39 are provided as there are liners 8 and are numbered to correspond to the numbers on the liners, the proper selector plate being attached to the disk 65 whenever a mold is placed on the disk. The link connection between the lever 30 and the indicator bar 26 imparts an adjustment to the operating rod 37 upon each adjustment of the selector operating lever 25 moving the rod 37 to a different 70 position of adjustment with respect to the mold disk upon each adjustment of the lever 25. The notches in the selector plates 39 are so positioned that when the selector operating lever 25 is properly positioned the finger 38 will be in alignment 75

with the notch of the plate 39 associated when the mold is in alignment with the ejector. Prior to the operation of the ejector the mold disk is given an axial forward movement. If the ejector selector lever is positioned properly, the finger 38 enters the notch in the plate 39 and the trip operating rod 37 is not actuated. However, if the ejector blade selector is improperly positioned the finger 38 will not enter the notch but will be engaged by the flange 42 of the plate and an endwise outward movement will be imparted to the rod 37.

The rod 37 has a threaded connection with an extension 44 which has a slot at its inner end 15 which receives the ball end 46 of a lever 47. Lever 47 is mounted in a substantially upright position and has a substantially horizontal portion adjacent its upper end which is journaled in a bearing carried by a bracket 48 secured to the 20 frame of the machine. A spring 49 is attached at its outer end to the extension 44 of the trip operating rod, and at its inner end to the lever 47 adjacent its upper end. The tension of the spring 49 tends to decrease the angle between 25 the rod 44 and the lever 47 drawing the rod 37 inwardly and holding the lever 47 in the inclined position shown in dotted lines in Fig. 4. At its lower end the lever 47 has a sleeve extension 50 in which is slidably mounted a rod 51 which has 30 a slot 52 to receive a pin 53 which holds the rod 51 against turning movement in the sleeve. The rod 51 is slidably mounted in the sleeve and is free to move up and down. Attached to the lower end of the rod 51 is a plate 54 which projects laterally from the rod 51 and rests upon the top edge 20 of the stopping lever 18. The plate 54 extends across the top edge 20 of the lever 18 and sufficiently past the same to intersect the path of the stopping pawl 23.

40 In the normal position of the lever 47, shown in dotted lines in Fig. 4, the plate 54 is positioned beyond the end of the pawl 23 and permits the pawl 23 to pass the stopping lever. If, however, the blade selecting lever should be improperly 45 positioned, the forward movement of the mold disk prior to the slug ejecting operation will cause the trip operating rod 37 to be moved forwardly, swinging the lever 47 to a vertical position and moving the plate 54 to the outer end 50 portion of the upper face 20 of the lever 18. In this position the plate 54 is in the path of the pawl 23 and engagement of the pawl 23 with the plate 54 will cause actuation of the lever 18 and operation of the clutch shifting lever 13 55 through the lower stopping lever 14.

The device of the present invention may be attached to a type casting machine without any alteration of any part of the machine and without any alteration of the adjustments of any of the operative parts of the machine. The trip plate 54 is held normally in an inoperative position on the lever upon which it rests and does not interfere in any way with the operation of the automatic safety stop controlled by the matrix transfer mechanism or with the automatic stopping of the machine upon completion of a cycle of operations.

No special adjustments of any part of the machine are required to insure the operation of the mold protector trip mechanism of the present invention.

It will be apparent that the present invention provides a very simple and effective means of preventing the stripping of mold liners due to

improper adjustment of the ejector blade selector.

Furthermore, it is to be understood that the particular form of apparatus shown and described, and the particular procedure set forth, are presented for purposes of explanation and illustration and that various modifications of said apparatus and procedure can be made without departing from my invention as defined in the appended claims.

What I claim is:

1. The combination with the movable mold carrier, the casting ejector mechanism and the adjustable ejector blade selector of a type casting machine, of a trip device having a movable element positioned adjacent the mold carrier, an angularly movable support for said movable element, means for connecting said support to said adjustable blade selector to adjust the support and movable element to a different position with 15 respect to the carrier for each adjustment of the blade selector, a selective trip actuator mounted on the mold carrier having trip actuating portions spaced apart a distance such as to permit passage of said movable element in one of its adjusted positions and impart a movement thereto during a movement of the carrier if the blade selector is in any position other than a predetermined position, and means controlled by said trip device for preventing operation of the casting 20 25 30 35 40 45 50 55 60 65 70 75 80 85 90 95 100 105 110 115 120 125 130 135 4. In a type casting machine having a rotatable and axially movable mold disk, a casting ejector mechanism, an adjustable ejector blade selector, a clutch controlled operating mechanism, and
5 means including a trip lever for disengaging the clutch to stop the machine, an automatic mold protector comprising a plate slidable on said trip lever into and out of the path of a part of said machine which moves in the direction in which
10 the trip lever moves to disengage the clutch, means for normally holding said plate in an inoperative position clear of said moving part, and means for actuating said plate comprising an operating member connected to the ejector
15 blade selector for adjustment simultaneously therewith and a selective actuating member carried by the mold disk, said operating member being operatively connected to said plate and having a part adjacent the mold disk with which
20 said actuating member engages upon an axial movement of the mold disk if the operating member is in any position other than a predetermined

adjusted position, said actuating member being formed to straddle and pass said operating member without engagement when said actuating member is in the said predetermined position and to engage and shift said operating member if it is not in the said predetermined position. 5

5. In a type casting machine having a clutch controlled operating mechanism, a trip lever for disengaging the clutch provided with substantially horizontal top face and a stopping pawl 10 which is normally positioned laterally of the lever to pass the same, an auxiliary trip device comprising a plate slidably mounted on the top face of said lever, said plate projecting laterally into the plane of movement of said pawl and 15 being movable on the lever into and out of the path of the pawl, a rod fixed to the plate, a lever telescopically engaging the rod, and means for actuating said lever to move the plate into the path of said pawl. 20

JAMES M. DENT.
